FOOD AND BEVERAGE SERVING SET

Ralph P. Wilton, Wrightsville, and John J. Fitzpatrick,
Hellam, Pa., assignors to Wilton Brass Company,
Columbia, Pa.

Filed Apr. 27, 1971, Ser. No. 138,010

Term of patent 14 years

Int. Cl. D7—01

U.S. Cl. D44—10 E

FIG. 1

FIG. 2

FIG. 3

FIG. 4

FIG. 1 is a side elevational view of a food and beverage serving set showing our new design;

FIG. 2 is a top plan view thereof;

FIG. 3 is an end elevational view thereof as seen from the left of FIG. 1;

FIG. 4 is an end elevational view thereof as seen from the right of FIG. 1, and;

FIG. 5 is a sectional view thereof taken along line 5—5 of FIG. 2.

The food and beverage serving set comprising the design of the present invention consists of a tray having recesses complementary to and separably receiving the dish and mug which also comprise part of the design.

We claim:

The ornamental design for a food and beverage serving
